No. 837,950.

PATENTED DEC. 11, 1906.

G. F. NOLTE,
RANGE.
APPLICATION FILED MAY 5, 1906.

UNITED STATES PATENT OFFICE.

GEORGE F. NOLTE, OF ST. LOUIS, MISSOURI.

RANGE.

No. 837,950.

Specification of Letters Patent.

Patented Dec. 11, 1906.

Application filed May 5, 1906. Serial No. 315,385.

To all whom it may concern:

Be it known that I, GEORGE F. NOLTE, a citizen of the United States, residing at St. Louis, State of Missouri, have invented certain new and useful Improvements in Ranges, of which the following is a full, clear, and exact description, reference being had to the accompanying drawings, forming a part thereof.

10 My invention has relation to improvements in ranges or stoves; and it consists in the novel details of construction more fully set forth in the specification and pointed out in the claims.

15 In the drawings, Figure 1 is a plan of the front of the range with portion of the top removed. Fig. 2 is a transverse vertical section on line 2 2 of Fig. 1. Fig. 3 is a longitudinal vertical section on line 3 3 of Fig. 1.

20 Fig. 4 is a perspective of the key for locking the center plate of the rear of the fire-box, and Fig. 5 is a sectional detail on line 5 5 of Fig. 2.

The present improvement has special relation to the fire-box of a cooking stove or range; and its specific object is to produce a construction eminently adapted to deliver air into the fire-box and at the same time provide means for heating the air in its passage 30 toward the fire-box and to keep cool the outer walls of the range.

A further object is to construct the rear wall of the fire-box out of a number of sections which can be assembled and readily 35 locked in place, all as will more fully appear from a detailed description of the invention, which is as follows:

Referring to the drawings, R represents a range, and F the fire-box thereof, whose 40 grate is represented by G. The fire-box is composed of the side walls 1 1', disposed parallel to the adjacent side walls of the range, said walls 1 1' being spaced from the range-walls and engaging the latter near the top by 45 a gradual curve c, Fig. 2, the upper rear corner of each wall 1 1' being provided with a web or wall 2 to afford for said wall a more extended bearing against the range - wall. The fire-box is further composed of the front 50 forwardly and upwardly inclined wall 3 and a rear rearwardly and upwardly inclined wall composed of the outer sections 4 4 and a central section 4', the oven O being directly in the rear of the wall 4 4' 4. The rear upper 55 edge of the section 4' terminates in a dovetail extension 4'', which fits snugly a corre-

sponding dovetail recess 5 of a key or plate 6, the latter being secured in position to the top of the oven, the edge of the dovetail recess being reinforced by a bead 7. Should it be desirable at any time to dismantle the fire-box, the key 6 is first removed, whereupon the section 4' is withdrawn, leaving the remaining sections free to be removed. The remaining walls of the fire-box are then also free to be removed from the range. That the middle section 4' may effectively lock the adjacent sections 4 4 in position, it is made to overlap the adjacent edges of said sections, as shown by the broken parts in Fig. 2 and also in the 70 sectional detail in Fig. 5.

As seen in Fig. 3, the front and rear walls of the fire-box are inclined to the front wall of the range and the adjacent wall of the oven O, the air-space between the fire-box 75 walls and the range-walls being in free communication with the air-spaces between the fire-box walls 1 1' and their adjacent range-walls, so that the several walls of the fire-box are virtually surrounded by an air-chamber, 80 to which the air entering from below the grate has free access. Of course this air has access to the fire-box through the grate G; but it is desirable in order to keep the outer walls of the range comparatively cool that 85 the air confined between the range-walls and fire-box walls shall freely circulate to admit fresh particles of air. This circulation is effected by providing means for the escape of the air into the fire-box, this method having 90 the additional advantage in that a maximum quantity of oxygen is supplied to the fuel. To accomplish this, I provide the walls 1 3 4 4' 4 with a series of bosses or nipples 8 distributed to the best advantage, each nipple 95 serving to deliver a jet of air through the inner end of a conical or tapering opening 9, formed jointly in the fire-box wall and in the nipple, the tapering character of the opening serving to insure the delivery of a positive 100 jet of air into the fire-box, and hence increasing the combustion and making available a maximum number of heat units contained in the fuel.

The top of the section 4' is provided with a 105 socket 10 for the insertion of the post 11, intended to support the top member of the stove between the lids thereof. Of course this post is a well-known expedient and I lay no claim thereto. The wall 1' is not provided with jet-nozzles 8, since this wall may 110 serve, in conjunction with the door D, as a

means of introducing fuel therethrough into the fire-box. Preferably the fuel is introduced by removing the lids, in which case the wall 1' need not be provided with any fuel-opening and the door D may then serve as an ornamental feature; but even should the wall 1' subserve no special function it need not be perforated for the admission of air into the fire-box, as practice has demonstrated that all the available oxygen may be introduced through the remaining walls of the fire-box and through the grate.

Having described my invention, what I claim is—

- 15 1. In a range, a fire-box composed of side and inclined front and rear walls spaced a suitable distance from the corresponding walls of the range, the rear wall being composed of a series of overlapping sections, the
- 20 middle section having a rear terminal dovetail extension bearing on the roof of the oven,

and a key secured to the oven-roof and having a dovetail recess for engaging the dovetail extension of the said middle section whereby the parts are securely locked, substantially as set forth. 25

2. In a range, a fire-box having a rear upwardly-inclined wall composed of a series of overlapping sections, a rear terminal dovetail extension for the middle section, a key or 30 plate having a dovetail recess for receiving said extension, the walls of the recess being bounded by a stiffening-bead, and means for securing the key to the top wall of the oven, whereby the sections are locked in position, 35 substantially as set forth.

In testimony whereof I affix my signature in presence of two witnesses.

GEORGE F. NOLTE.
